(57) CLAIM

The ornamental design for a mascara package, substantially as shown and described.

DESCRIPTION

FIG. 1 is a top, front perspective view of our new design for a mascara package;

FIG. 2 is a bottom, rear perspective view of the mascara package shown in FIG. 1;

FIG. 3 is front elevation view of the mascara package shown in FIG. 1;

FIG. 4 is a right side elevation view of the mascara package shown in FIG. 1, the left side view being a mirror image thereof;

FIG. 5 is a rear elevation view of the mascara package shown in FIG. 1;

FIG. 6 is a top plan view of the mascara package shown in FIG. 1;

FIG. 7 is a bottom plan view of the mascara package shown in FIG. 1; and,

FIG. 8 is front elevation view of the mascara package shown in FIG. 3, with the cap removed.

The broken line showing in FIGS. 1, 3, 4, 6 and 8 is presented for illustrative purposes only and forms no part of the claimed design.
